UNITED STATES PATENT OFFICE.

THEODORE SANDERS, OF DANBURY, CONNECTICUT, ASSIGNOR OF TWO-THIRDS TO J. B. NICHOLS AND E. A. HINE, BOTH OF SAME PLACE.

MACHINE FOR PINNING OUT HATS.

SPECIFICATION forming part of Letters Patent No. 328,719, dated October 20, 1885.

Application filed June 22, 1885. Serial No. 169,409. (No model.)

To all whom it may concern:

Be it known that I, THEODORE SANDERS, a citizen of the United States, residing at Danbury, in the county of Fairfield and State of Connecticut, have invented certain new and useful Improvements in Machines for Pinning Out Hats; and I do hereby declare the following to be a full, clear, and exact description of the invention, such as will enable others skilled in the art to which it appertains to make and use the same.

My invention relates to certain novel and useful improvements in machines for pinning or wringing out hat-bodies after the operation of sizing and just before the process of drying, and has for its object to provide a machine of this description which shall greatly facilitate the pinning out or wringing and improve the quality of work done; and with these ends in view my invention consists in certain details of construction and combination of elements, hereinafter explained, and then specifically designated by the claims.

In order that those skilled in the art to which my invention appertains may fully understand its construction and operation, I will proceed to describe the same in detail, referring by letter to the accompanying drawings, forming a part of this specification, in which—

30 Figure 1 is a front elevation, and Fig. 2 a side elevation, of my improvement.

Similar letters denote like parts in both the figures of the drawing.

A is the frame, of convenient shape to support the operative parts of the machine. Journaled within this frame, at B, are vertical shafts C, preferably three in number, supporting at their upper extremities conical rolls or supports D.

40 E are beveled gear-wheels loosely journaled on the lower ends of the shafts C, and therefore free to revolve independently thereof. Just above these beveled gears and splined to the shafts C are clutches F, having teeth or serrations a, adapted to engage with corresponding projections, b, on the back of the gear-wheels.

45 G is a lever, whose outer end embraces and operates the clutch. There are as many of these levers as there are clutches, and they

are fulcrumed to the frame at c, and are connected by rods H to the treadles I, which latter are pivoted to the back of the frame and extend forward to within convenient reach of the operators.

55 J is a counter-shaft journaled within the lower portion of the frame, and having secured thereon beveled gears K, adapted to mesh with the gear-wheels E.

Opposite each of the shafts C is an oblique 60 shaft, L, journaled within the boxes M N, the latter of which is adjustable in the direction of the arrow by means of the threaded rod O, engaging with threads in the frame, and swivelly attached to said box.

65 Formed integral with the box M is a pin, P, which projects through the frame, as shown in Fig. 2.

Also formed with the box M is a threaded pin, Q, on which is run a hand-nut, R, for the 70 purpose presently explained.

S is a bar secured to the frame, and extending lengthwise thereof just back of the pins Q. Between this bar and the hand-nut is interposed coil-spring T, the tendency of which 75 is to keep the box in its normal position against the frame.

U is a conical roll, supported on the upper end of the shaft L, and normally in contact with the roll D.

80 V is a lever, pivoted to the frame at d, the upper end being in contact with the end of the pin P, and the lower end connected with the treadle by rod W, so that it will be seen that by depressing the treadle the pin P, and 85 with it the box M and shaft L, will be forced back against the action of the spring T, the object of which will be hereinafter explained.

X are rods fulcrumed at e to the frame, and loosely passed through openings on the rod H, 90 and thereby connected to the treadle. The upper ends of the rods X are bent at an angle and extend alongside of the rolls D, and are somewhat resilient.

95 From the foregoing description the operation of my improvement will obviously be as follows: The counter-shaft is caused to revolve by belting in the ordinary manner, which imparts motion to the beveled gear-wheels E. The operator, by depressing one of the foot- 100

treadles I, will force the corresponding roll, U, out of contact with its roll D, and at the same time disengage the clutch from the gear-wheel E, as before explained, thus causing the roll 5 whose treadle was operated to stop revolving.

The hat-body is now placed over this roll and its rod X, the latter taking up the slack to prevent folding or creasing. The treadle is now released, allowing the oblique roll to 10 bear against the hat-body and the clutch to engage with the gear, causing the roll to revolve. This, it will be seen, will bring every portion of the hat-body under the pressure of the oblique roll, which pressure may be varied 15 by operating the hand-nut Q to change the tension of the spring. The pressure thus brought to bear upon the hat-body will remove all the surplus water therefrom without causing crozing-marks, as but one surface is 20 acted upon.

Heretofore the operation of pinning out invariably caused crozing-marks to be left in the hat-bodies, which have to be removed by pounding or the like, and the inability to remove 25 all the dead water by the present hand operation causes much expense and loss of time in drying.

If it is desired to increase the pressure on the upper and decrease it on the lower portion 30 of the hat-body, it is only necessary to elevate the box N, and with it the lower end of the shaft L, by manipulating the threaded rod O. The reverse will take place by lowering said box and shaft.

35 In the drawings I have shown three sets of rolls, as I deem this the proper number for an operator to manipulate; but, of course, this is immaterial, as any number may be used; also, I do not wish to be confined to the exact shape 40 of the rolls, as this may be altered without departing from the spirit of my invention.

Having thus fully described my invention, what I claim as new and useful is—

1. In a machine as described, the vertical 45 support D, mounted upon the shaft C, the latter being provided at its lower extremity with clutch mechanism for controlling its rotation, in combination with the roll U, the spring-actuated box M, and adjustable box N, substantially as shown and described.

2. In a machine as described, the vertical support D, shaft C, clutch F, beveled gears E 50 K, and shaft J, in combination with the roll

U, box M, pin P, and means for operating said pin against the action of the spring T, as 55 shown and specified.

3. In a machine as described, the support D, mounted upon the upper end of the shaft C, the lower end of which is provided with a clutch, F, adapted to engage with the projection on the beveled gear, in combination with means for disengaging said clutch and gear and means for rotating the latter, as shown and specified.

4. The combination of the support D, shaft 60 C, clutch F, and means for operating the latter, gears E K, and counter-shaft J, with the pressure-roll U, oblique shaft L, adjustable box N, spring-actuated box M, having formed therewith the pin P, lever V, connecting-rod 70 W, and treadle I, all arranged to operate as described.

5. Support D, mounted upon the shaft C, the latter being provided with the clutch F, and beveled gear E, in combination with the 75 lever G, shod to said clutch, and the connecting-rod H, attached at its lower end to the treadle I and at its upper end to the rod X, substantially as shown and described.

6. In a machine for pinning out hats, the 80 vertical shaft C, having mounted upon its upper end the support D and loosely journaled on its lower extremity the beveled gear E, clutch F, splined to said shaft and adapted to be operated by the treadle through the rod 85 H and lever G, substantially as shown, and for the purpose set forth.

7. In a machine for pinning out hats, a support for the hat-bodies capable of rotation, in combination with an adjustable roll adapted 90 to act against the hat throughout its entire circuit, substantially as shown and described.

8. In a machine for pinning out hats, the combination, with a support for the hat capable of rotation and an adjustable roll adapted 95 to act against the hat, of a spring-rod extending upward between said support and hat, whereby any slack is taken up and the occurrence of crozing-marks prevented, substantially as set forth.

In testimony whereof I affix my signature in presence of two witnesses.

THEODORE SANDERS.
